UNITED STATES PATENT OFFICE.

THOMAS PARKER OTTERSON, OF KREBS, OKLAHOMA, ASSIGNOR OF ONE-HALF TO
PRESLEY ROBINS ALLEN, OF McALESTER, OKLAHOMA.

DRAW-BAR.

1,255,781.

Specification of Letters Patent.

Patented Feb. 5, 1918.

Application filed August 11, 1917. Serial No. 185,772.

To all whom it may concern:

Be it known that I, THOMAS PARKER OTTERSON, a citizen of the United States, residing at Krebs, in the county of Pittsburg 5 and State of Oklahoma, have invented new and useful Improvements in Draw-Bars, of which the following is a specification.

This invention relates to draw bars for coupling cars and particularly mine cars.

10 In the present couplings for mine cars, links, pins, hooks and other devices are used, but all are more or less unsatisfactory as they will not stay coupled or connected in view of the irregularity in level and lineal 15 disposition of mine seams. Mine seams will run level for a certain limited distance and then pitch heavily to another level and thus continue to vary throughout the entire seam extent and also swerve or turn at various 20 angles, and, as a consequence, great difficulty is encountered in maintaining mine cars in practical coupled relation in following a seam, and when they break loose numerous accidents and injury to operatives 25 result.

The main object of the present improved draw or coupling bar is to provide a device that is simple in construction and operation and effective in maintaining mine cars in 30 coupled condition irrespective of grade variations or lateral deflections in the travel of mine cars.

With this and other objects and advantages in view, the invention consists in the 35 construction and arrangement of parts which will be more fully hereinafter described and claimed.

In the drawing:—

Figure 1 is a plan view of a mine car with 40 the improved draw bar secured therein.

Fig. 2 is a cross sectional view of the car and bar.

Fig. 3 is a detail perspective view of the draw or coupling bar.

45 Figs. 4, 5 and 6 are detail perspective views of one extremity of the bar, the safety locking latch, and the latch or keeper pin.

Fig. 7 is a perspective view of a double form of the improved bar.

50 The letter A designates a mine car of usual form and construction, and centrally therein the improved device is mounted and consists of a flat bar 5 of suitable length and thickness, and having at one end a coupling hook or head 6, as shown by Figs. 1, 3 and

4, or similar hooks or heads 6 and 7, as shown by Fig. 7. Each hook or head has a throat 8 opening outwardly through one side at a slight inward angle, or, the throats of the bar, as shown by Fig. 7, open reversely through the bar sides. On one side of the bar 5 is a safety latch or latches 9 and 10 and each has its inner extremity pivoted to the bar, as at 11, the outer end of each latch being in the form of a hook 12 60 with a throat 13 opening through the side thereof at a rearward angle. The throat 13 of each latch opens through the side thereof of opposite or reverse to the throat 8 of the adjacent coupling hook or head of the bar 65 5 with which it coacts, and, hence, when each latch is closed and locked the throat 8 of either of the hooks or heads 6 and 7 is positively closed thereby. The hook 12 of each latch is of the same dimensions and 70 contour as the head of the bar 5 and when said latch head 12 is closed relatively to the bar head the edges of the two heads coincide. Each latch has an opening 14 therein 75 in longitudinal alinement with its pivot 11, 80 and in said opening 14 a locking pin 15 is loosely mounted and provided with a loop or eye head 16. The bar 5 also has an opening 17 therein at one or both extremities adjacent to but in rear of each head 85 thereof and in alinement with the pivot 11 of each latch. When each latch is closed over its bar head, the opening 14 of the latch registers with the adjacent opening 17 and the pin 15 drops into said latter opening, 90 thereby locking the latch against movement and preventing accidental disengagement of the coupling means from the bar head and latch. When release of the coupling means from the bar head and adjacent 95 locking latch is desired, it is only necessary to raise the pin 15 to clear the opening 17 and the latch may then be turned on its pivot 11 to clear the bar head and throat 8 when the link or coupling means may be 100 readily withdrawn. Links 18 are illustrated as the coupling means to coact with the improved draw or coupling bar, said links being suitably attached to adjacent draw bars in coupling the mine cars. Any 105 other form of coupling means may be used, and the improved draw bar may be applied to any other car or vehicle.

The bar 5 is of such width and the pin 15 is carried in such position in connection 110

with each safety latch that when the pin is raised or pulled up to release the latch it will remain in such raised position for automatic operation or locking action or be ready to drop in the opening 17 when the latch is closed, and registration of the openings 14 and 17 ensues. The inward angular deflections of the throats 8 and 13 of the bar head and latch conjointly act to draw the coupling means into the centers or eyes of the head and latch and also obstruct the accidental release of said coupling means when the latch is locked closed.

The improved draw or coupling bar is cheap in the cost of manufacture and may be easily applied in operative position to effectively perform its functions. If the pins 15 fail to work or lock in the openings 17, the coupling devices or links would still be held in the bar head and latch by reason of the particular mounting of said latch as explained, and in view of this structural advantage of the improved bar, its reliability and efficiency as a draw and coupling means are materially increased.

What is claimed is:—

1. A device for the purpose specified, consisting of a bar having a hooked end head with a throat opening through the side edge thereof at an angle toward the rear end of the bar and also provided with an opening in rear of said throat, a safety latch pivotally mounted and movable on the bar and having a hooked head corresponding to the bar head and formed with a similar throat opening through the one side edge thereof and reversely to the throat of the bar head, and a pin loosely mounted and vertically

movable in the latch to engage the said opening in rear of the bar head throat to lock the latch against movement.

2. A device for the purpose specified, consisting of a bar having one or more hooked end heads and one or more pivoted latches thereon, with reversely arranged side opening throats each latch carrying a loose vertically movable pin to automatically engage the bar and lock the latch closed.

3. A device for the purpose specified, consisting of a bar having one or more hooked end heads and one or more pivoted latches thereon; each head and latch having reverse laterally opening inwardly inclined throats and each latch carrying a loose vertically movable pin to automatically engage the bar and lock the latch closed.

4. A mine car having a draw bar centrally and longitudinally disposed therein and provided with a coupling head having a laterally opening inwardly inclined throat, a safety latch pivoted upon and movable over said bar head and also having a hook head with a laterally opening inwardly inclined throat reversely extending relatively to the bar head throat, and a keeper pin loosely carried by and vertically movable in the safety latch to automatically engage the bar and lock the latch against movement.

In testimony whereof I have hereunto set my hand in presence of two subscribing witnesses.

THOMAS PARKER OTTERSON.
